COMBINATION STORAGE AND DISPLAY CONTAINER FOR RETAINING RINGS OR THE LIKE

Joseph M. Bruening, Shaker Heights, Ohio

Application August 8, 1958, Serial No. 52,128

Term of patent 14 years

(Cl. D80—5)

Fig. 1 is a perspective view of a combination storage and display container for retaining rings or the like embodying my new design;

Fig. 2 is a fragmentary horizontal sectional view on the line 2—2 of Fig. 1; and

Fig. 3 is a top plan view of the container in closed condition.

The essential features of my new design for a combination storage and display container for retaining rings or the like reside in the three ring holding recesses having the configuration as shown.

I claim:

The ornamental design for a combination storage and display container for retaining rings or the like, as shown and described.
